CONTAINER FOR THE TRANSPORTATION
OF GOODS

Michel Marie Jean Lefevre-Utile, Paris, France

Application April 6, 1933, Serial No. 664,824
In France May 21, 1932

3 Claims. (Cl. 105—366)

The object of my invention is to provide a container for transportation of goods capable of travelling by railway, motor vans, ships, etc., and more particularly of boxes that can be arranged on shelves.

While the containers that have been used up to this time consist of panels rigidly assembled together, the container that is the object of the present invention consists essentially of a metallic frame which carries the panels or elements forming the container, and which is intended to support the stresses due to the handling of the container, and especially to its hauling for placing it on the platform of railway cars, motor vans or carriers, and for removing it therefrom. Said frame is suitably braced and provided with hooks or rings for permitting its handling and transshipment.

The box formed by the panels and placed on the frame is divided on the inside, on either side of a central passage, into compartments provided with shelves in which the articles to be transported are arranged. The passage further comprises pivoting shelves which can be swung into their operative position, and loaded with goods.

Finally, the container is closed by one or two doors which can be locked and sealed.

A preferred embodiment of the present invention will be hereinafter described with reference to the accompanying drawings given merely by way of example, and in which:

Fig. 1 is an outer view of the container placed on a carrier;

Fig. 2 is a perspective view of the metallic frame of the container;

Fig. 3 is a perspective view of the inside of the container;

Fig. 4 shows a pivoting shelf;

Fig. 5 is a plan view of a portion of the inside of the container.

The frame of container 1 (Fig. 1) consists of two transversal members 3, supporting two longitudinally disposed sectional irons 4 connected at their ends by transversally disposed sectional irons 5.

That structure is completed by two longitudinal members 6, the whole being assembled and braced by means of gussets 1. That structure further carries four upright members 8 which are connected together at their upper part by transversal members 9, and by diagonal braces 10. At the upper end of each of said upright members 8, there is fixed a ring 11 which permits to hang the container and to perform the transshipment by means of any suitable hoisting machine.

The elements that form the container proper, (floor, side walls, roof, etc.,) are placed on the frame that has just been described.

This parallelepipedic box 1, is preferably made of wood outwardly cased with sheet iron, and is made isothermal by inserting for instance sheets of an insulating material between the walls, so as to leave a small air cushion between two thicknesses. It is divided on each side of a central passage closed by a door 2, into a certain number of compartments 12 (Fig. 3) which may for instance be three in number. Each of said compartments may itself be divided in a vertical direction, into several spaces, three of them for instance, by means of shelves, and the goods to be transported and more especially boxes, are arranged on said shelves.

Pivoting shelves 13, shown in detail in Fig. 4 are pivoted to the edges of the shelves above referred to. They consist of two elements 13^a and 13^b connected together through iron fittings 16 which are provided with stops 16^a intended to keep the portions 13^a and 13^b in line with each other when shelf 13 is unfolded. Portion 13^a is connected through hinges 14 to sectional irons 15 that form the edges of the stationary shelves. When it is folded down, shelf 13 is in the position shown in dotted lines in Fig. 5 and extends across the central passage so that supplementary articles or boxes can be arranged thereon in said passage.

Finally, two opposite compartments and the portion of the passage extending between them can be separated from the remainder of the container by door 17 shown in Figs. 3 and 5.

In order to load the container, I first fill, for instance with boxes, the shelves of the compartment most remote from the door, that does not carry pivoting shelves 13. I then fold down said shelves 13 across the passage, and I fill said pivoting shelves and the stationary shelves by which they are carried. I then close intermediate door 17, and fill the other compartments as above explained. When the container is full, the outer door of the passage is closed, and can be locked and sealed.

Of course, the number of shelves and compartments that are shown in the drawings has been given merely by way of example, and can be modified.

While I have described what I deem to be practical and efficient embodiments of my invention, it should be well understood that I do not wish to be limited thereto as there might be changes made in the arrangement, disposition and form

of the parts without departing from the principle of my invention as comprehended within the scope of the appended claims.

What I claim is:

- 5 1. A shipping container, which comprises in combination, a metal frame, panels carried by said frame so as to form the walls, top and bottom of the container, said frame including a plurality of upright members disposed at a fixed distance inside said walls, and fastening means carried by the tops of said upright members respectively, whereby the container can be readily connected to hoisting means.
- 10 2. A shipping container which comprises, in combination, a metal frame, panels carried by said frame so as to form the walls, top and bottom of the container, said frame including a
- 15

plurality of upright members disposed at a fixed distance inside said walls, and rings carried by the tops of said upright members respectively, whereby the container can be readily connected to hoisting means.

3. A shipping container which comprises, in combination, a metal frame, panels carried by said frame so as to form the walls, top and bottom of the container, said frame including a plurality of upright members disposed at a fixed 10 distance inside said walls, vertical partitions extending between said upright members and said walls, and fastening means, carried by the tops of said upright members respectively, whereby said container can be readily connected to hoist- 15 ing means.

MICHEL MARIE JEAN LEFEVRE-UTILE.
